UNITED STATES PATENT OFFICE.

NATHAN KASDAN, OF NEW YORK, AND DANIEL POLLACK, OF BROOKLYN, NEW YORK,
ASSIGNORS TO MAJESTIC METAL SPECIALTIES, INC., OF NEW YORK, N. Y., A COR-
PORATION OF NEW YORK.

VANITY CASE.

Application filed December 8, 1925. Serial No. 73,974.

This invention relates to vanity cases preferably of the type used for carrying face powder, and provided with a mirror. One of the objects of the invention is to provide 5 a mirror which is pivotally mounted on one of the members of the case so that it may swing in a plane parallel to the plane of the member to which it is attached so as to act as a cover for a compact carried by 10 said member, said mirror being provided with means for automatically moving it into extended position upon said member, and a stop being provided to limit the swinging movement of said mirror. Other objects of 15 the invention are to provide controllable means for restraining a mirror against movement when urged to move by a spring. Other objects of the invention are to provide a novel construction of vanity case 20 adapted to hold two compacts of suitable powder, and to generally improve the construction of vanity cases.

These being among the objects of the present invention, the same consists of certain features of construction and combinations of parts to be hereinafter described 25 and then claimed with reference to the accompanying drawings illustrating a preferred embodiment of the invention in which:

Fig. 1 is an enlarged section of the vanity case;

Fig. 2 is a longitudinal section on the line 2-2 of Fig. 3;

Fig. 3 is a plan of the vanity case showing 35 the case open and the mirror extended to uncover the compact thereunder;

Fig. 4 is a sectional plan on the line 4-4 of Fig. 2, as viewed in the direction of the arrows;

Fig. 5 is a sectional plan on the line 5-5 of Fig. 2;

Fig. 6 is a detached plan view of one of the interfitting plates of the case;

Fig. 7 is a plan of another plate constituting a deck plate;

Fig. 8 is a bottom plan of the mirror plate;

Fig. 9 is an enlarged detail section on the line 9-9 of Fig. 8;

Fig. 10 is an enlarged sectional detail showing how the mirror is pivotally mounted and spring actuated, the mirror being here shown as swung outwardly;

Fig. 11 is a broken plan view showing

further details of the mounting and of the actuating spring for the mirror;

Fig. 12 is a detail section showing how the mirror is held against actuation by the spring;

Fig. 13 is a section on the line 13-13 of Fig. 12; and

Fig. 14 is a perspective view of the mirror actuating spring.

Preferably all of the structural parts of the improved vanity case are composed of sheet metal, and the case comprises a flanged body or box member 15 and a lid member 16. Preferably the members 15 and 16 are elongated and formed with rounded outer flanges which taper at 17-17^a toward straight edges or flanges 21-21^a. The shape of the said members is well shown in Fig. 3. The flanges 17-17^a are joined by means of hinges 18, the leaves of which are formed with prongs 19-20 which are passed through holes on the straight flanges 21-21^a and then riveted or turned down against the inner surfaces of said flanges. Incidentally, the riveted or turned-down inner ends of the prongs 19-20 provide projections at the inner surfaces of the flanges 21-21^a. The case may be held closed by means of a suitable snap fastening 21^b which is preferably mounted on the body member 15 so that its catch may be engaged with a portion of the lid member 16 in well-known manner.

Small projections 22-23 are struck inwardly from the members 15 and 16, respectively. The projections 22 cooperate with the prong projections 20 to hold in place a plate 24 which substantially conforms to the space within the flange of the body member, and it is adapted to be sprung and fitted into the body member against the inner surface of its bottom. Thereby the plate 24 is securely and rigidly held in position. The inner end of the plate 24 at a point adjacent the hinge 18 is provided with a clip 25 preferably consisting of a tongue formed integrally with the plate 24 and bent upwardly and inwardly so as to form a clip for the purpose of holding a lip stick 26 removably in position.

The supporting plate 24 is provided with a large aperture 27 which is offset with respect to the center of the plate, said aperture being defined by an inner flange 28 which is pressed out from the plate in a

plane raised from the plate. Said flange 28 is provided with a downwardly bent portion 29 which constitutes a friction snap catch. This catch is adapted to frictionally and securely hold in position a dished compact holder 30. The compact holder 30 may contain a compact of white face powder, for example.

Within the flange of the lid member 16 there is held a deck plate 31. This plate is held in place by the conjoined action of projections 19 and 23. The supporting plate 24 and the deck plate 31 are shaped to conform to the flanges of the body and lid members within which they fit, and the shape is preferably somewhat like a key-stone with its wider edge convexly curved. The plate 31 is provided with a deck 32 which is offset from the center of the plate and is raised to the desired extent above the plane of said plate. The deck 32 is provided with a large aperture 33 which is defined by an inner flange 34. The flange is formed preferably with an integral projecting portion 35 constituting a friction snap catch. This catch 35 is preferably located at one side of the aperture 33, while at the other side of said aperture there is preferably formed integrally with the deck a retaining lip 36 which extends inwardly towards the center of the aperture. By the conjoint action of the snap 35 and the retaining lip 36 a dished compact holder 37 is held removably in position in the deck plate.

A preferably circular sheet metal plate 38 is provided and is adapted to form the frame of a mirror 39 suitably held to the frame. The mirror plate 38 is provided with a stud 40 which is formed by striking up a portion of the plate 38 so as to form a hollow tubular pivot. The inner end of the hollow pivot is cut and a lip 41 is slightly bent out from the same, as shown in Fig. 9. As shown more fully in Figs. 9, 10 and 11, a helical spring 42 is provided, the end 43 of which is placed under the lip 41 which is then pressed down so as to hold said end of the spring securely. Fitted over the stud or pivot 40 is a bearing collar 44 which is formed integrally with the deck 32, said collar constituting a bearing so that the mirror may swing on the pivot. The tail 45 of spring 42 as shown in Fig. 14 is considerably extended and as shown in Fig. 11 is adapted to bear outwardly on the deck plate 31. It will thus be seen that the stud or pivot 40, the bearing collar 44, and the helical spring 42 are confined in the annular space afforded by the described formation of the deck plate.

A spring or friction catch 46 is secured to the deck 32 of the deck plate in such position that its engaging end may be snapped over the rim of the mirror frame or plate 38 and hold it together with the mirror in such po-

sition as to cover the compact in the holder 37. When the said mirror and plate or frame are so secured by the catch 46 they will substantially coincide with the deck 32 of the deck plate. To swing the mirror to such position, it is necessary to overcome the outward tendency of the prong 42, and to restrain the tendency of said spring to urge the mirror outwardly a spring or friction catch is desirable. Inasmuch as the mirror is adapted to swing in a plane substantially parallel with the deck plate, the described spring catch 46 is also designed to constitute a stop to limit the outward throw of the mirror when impelled by the spring. The mirror is shown in its outward position in Fig. 3 where its movement has been limited by the stop 46.

It will be seen from the above description in connection with the drawings that a number of other advantages than those mentioned are gained by the improved construction. For instance, no separate pivot is required for the mirror, as the pivot is preferably formed by deflecting a portion of the stock of the sheet metal plate 31, and which may be cut so as to provide simple means for holding one end of the actuating spring. Also another advantage incidental to the improved construction and particularly to the design of the improved vanity case is that the two main members thereof are of such size that when open they may be conveniently grasped in one hand, while the slidably mounted mirror may be restrained from movement by the simple expedient of the catch 46, the mirror being easily releasable from the catch by a slight inward movement of the thumb of the hand which is holding the case.

These and other incidental advantages will be obvious to those skilled in the art, and it is clear that the invention is susceptible of more or less modification and that the scope of said invention is not limited except as defined in the appended claims.

What we claim as our invention and desire to secure by Letters Patent, is:

1. A vanity case having in combination an apertured plate, a flange at the edge of the aperture, and a friction snap catch extending from the edge of the aperture, and a dished compact holder fitted in said aperture against said flange and held therein by said snap.

2. A vanity case having in combination an apertured plate, a flange at the edge of the aperture, a friction snap extending from one side of the edge of the aperture, a retaining lip extending from the other side of the edge of the aperture, and a dished compact holder fitted in said aperture against said flange and held therein by the mutual action of the said snap and retaining lip.

3. A vanity case, comprising an apertured

plate, means for retaining a compact holder in the aperture, said plate having a laterally extending supporting portion, and a clip formed integrally with the said laterally extending portion for retaining a lip stick on said portion.

4. A vanity case, comprising a receptacle receiving member, a mirror carrying plate having a portion of its stock struck up to

form a hollow pivot, the end of the pivot being cut to form a lip, the pivot journaled in said member, and a coiled spring about the journal, one end of the spring being secured by said lip and the other end bearing against said member.
